UNITED STATES PATENT OFFICE

2,100,173

CLOSURE DEVICE

Harry Ernest Rubens, New York, N. Y.

Application February 23, 1935, Serial No. 7,730

1 Claim. (Cl. 132—80)

This invention relates to improvements in closure devices for collapsible tubes and more particularly to a closure device containing a readily accessible compartment within said device for storing and holding subsidiary articles used in conjunction with the contents of the tube, such as a styptic pencil for shaving cream, a small eyebrush for mascara cream, and a wide variety of additional uses.

10 One object of my invention is to provide such a compartment which shall be readily accessible to the user by unscrewing the cap for the closure device or by a push-fit engagement in which the cap may be readily loosened from the device by turning or rocking slightly on its engaging support.

Another object is to provide such a compartment for such a device in which its contents may be easily renewed, if necessary, as for instance if the novel closure device is transferred to another tube containing the ordinary closure cap, and it becomes necessary to renew the contents of the device.

Another object is to provide a compartment for a closure device which shall be moisture proof, and air tight, yet its contents shall be readily accessible to the user.

Other objects shall become apparent when the following description is read in conjunction with the accompanying drawing in which—

Fig. 1 is a fractional elevation of a collapsible tube provided with a closure device according to the principles of my invention, part of the closure device shown in section;

Fig. 2 is a similar view, showing a modification of the closure device in vertical section;

Fig. 3 is a view of a cap for said closure device, containing a small brush integral thereto for use with the contents of tube or compartment;

Fig. 4 is a vertical cross section of an additional closure modification with styptic pencil captured therein;

Fig. 5 is a bottom view of said closure device.

I am aware that closure caps have hitherto been used for dispensing dental floss and that styptic pencils have been used in razors of the safety type. However, the inventive concept hereinafter described advances the art in a manner unknown and contributes a novel and useful article designed to be given away with the collapsible tube, the additional expense so minute as to be absorbed by the manufacturer.

Referring to Fig. 1, a collapsible tube 10 is provided with a threaded neck 11, in the well-known

manner. To the threaded neck 11, an auxiliary bushing 12, is shown, hereinafter described.

The tube 10 is provided with a closure device 15, containing an inner compartment, various modifications of which are shown in Figs. 1, 2, 3 and 5.

In Fig. 1 the closure device is provided with an inner threaded portion 15a for engagement direct with said aforementioned threaded neck 11, or if the bushing is desired, with said bushing 12.

The closure device 15 has the usual knurled shoulder 15c, or it may be moulded square to provide the grip for convenient manual operation.

The closure device 15 is further provided with a recessed chamber on its upper surface formed 15 by the tubular extension 15b, forming a partition 15d. Within this recessed chamber, any desired articles in stick form such as 16 may be inserted and permanently attached as by gluing, or closely fitted to normally remain therein. Above the recessed chamber and either in screw or push fit engagement with the tubular extension, a metal or composition thimble 18 is provided for keeping the contents air-tight and free from exposure. The thimble 18 may be knurled for ease in handling.

A modified form of the closure device is shown in Fig. 4, which consists in allowing the dispensing stick 16 to be inserted from the tube opening or within the threaded section 15a. The stick 16 is provided with a shoulder 16a which engages the closure device and prevents the stick 16 from becoming loose and lost. Behind the shoulder 16a the usual foil covered cork washer 17 is inserted and the pressure of the neck 11 of the tube 10 keeps the stick 16 rigid and in place when the thimble or cover 18 is removed and the stick is in use.

In Fig. 2 the closure device is shown in tubular formation, 15A, internally threaded at each end, 40 and a partition 15d seals the inner chamber 15B from one end of the closure device; namely, the tube neck end. The other internally threaded portion is provided with an engaging threaded cap 20, knurled for convenience, which seals the 45 inner chamber which is the only means of access to said chamber.

In Fig. 2, a modified form of cap 20 is shown, reversibly mounted on the closure device 15A, with 50 a styptic pencil 16, inserted therein. Provision is made in this modification for reversing the position of the styptic pencil, so that it may be completely enclosed in the inner chamber 15B. To this end, the knurled finger section 20, divides

the cap into two sections, the threaded portion 22 for engagement with the internally threaded closure device 15A, as shown, and the cylindrical wall section 23, into which the stypic pencil 16 5 fits and partially extends beyond for use. When not in use, the cap is reversed, the dotted lines indicating the position of the pencil 16, within the chamber, the threaded outside of the cylindrical walls engaging the internally threaded closure 10 device 15A. In this position, it resembles the structure shown in Fig. 3, except that a brush 21 is substituted there for the stypic pencil 16.

In Fig. 3, the cap 20 is shown, provided with a small eyebrow brush 21 in conjunction with a 15 mascara paste, or nourishing cream. A brush may also be used in conjunction with a shoe whitener, etc.

In addition, the present invention by an unusual arrangement of cover and contents enables 20 the tube user to use the tube as a handle, as for instance in Figs. 1 and 2 the thimble 18 may be removed, and the stick possibly made of a stypic composition for use in conjunction with shaving 25 cream for shaving purposes would be rigid with the tube itself, which could conveniently be used as a handle.

The cover cap 20 may be used as a support for a brush 21, see Fig. 3, in conjunction with the

tube contents for supporting the stick 16, as shown in Fig. 2, as previously explained.

The cap 20 may be threaded as shown in Fig. 2, or it may be threaded along its entire longitudinal axis, or as previously discussed above the outer portion as at 22 in Fig. 3, so that the brush or stypic pencil may be unscrewed from the position as shown and reversed so that the brush or pencil is exposed and rigid with the tube for convenience in handling.

The invention is susceptible of a variety of mechanical expressions and uses including rigidly attached or loosely enclosed sticks such as a lipstick or deodorants, etc., for powders, brushes, tablets and especially liquids, such as glues, anti-septics, lacquer removers for finger nail compounds, etc.

Having now described my invention, what I claim and desire to secure by Letters Patent, is:—

In a collapsible tube for containing a paste-like composition having a neck; a closure cap thereon and having a closed head and a cylindrical wall section extending therefrom; a dispensable article partially contained within said cylindrical wall section and extending beyond for dispensing purposes, whereby when said article is being dispensed, the tube may serve as a handle for supporting the same.

HARRY ERNEST RUBENS.
